CLAIM

The ornamental design for a strap length adjustment clip as shown and described.

DESCRIPTION

FIG. 1 is a front top right perspective view of a first embodiment of the strap length adjustment clip showing my new design;

FIG. 2 is a front bottom left perspective view thereof;

FIG. 3 is a front elevational view thereof;

FIG. 4 is a rear elevational view thereof;

FIG. 5 is a right side view thereof;

FIG. 6 is a left side view thereof;

FIG. 7 is a top view thereof;

FIG. 8 is a bottom view thereof;

FIG. 9 is a front top right perspective view of a second embodiment of the strap length adjustment clip showing my new design;

FIG. 10 is a front bottom left perspective view thereof;

FIG. 11 is a front elevational view thereof;

FIG. 12 is a rear elevational view thereof;

FIG. 13 is a right side view thereof;

FIG. 14 is a left side view thereof;

FIG. 15 is a top view thereof; and,

FIG. 16 is a bottom view thereof.

The first embodiment is shown with two symbolic breaks in its length. The appearance of any portion of the clip between any bracketed adjacent pair of break lines forms no part of the claimed design
